AIRFOIL

Harry M. McKay, Ferguson, Mo., assignor to St. Louis Aircraft Corporation, St. Louis, Mo., a corporation of Missouri

Application October 14, 1939, Serial No. 299,416

3 Claims. (Cl. 244—123)

This invention relates generally to airplanes. More particularly, this invention relates to a certain new and useful improvement in airplane wings or so-called airfoils and has, briefly stated, for its chief objects the provision of an airfoil which is so uniquely constructed of co-operable readily joined and connected parts that its production and fabrication may be accomplished and effected speedily as to time and economically as to labor and material and which has such a unique frame of obliquely disposed cells that, while light in weight, structurally has form, strength, and durability capable of successfully, and without deformation or loss of normal shape, resisting and withstanding great strains and 15 stresses.

And with the above and other objects in view, my invention resides in the novel features of form, construction, arrangement, and combination of parts presently described and pointed out in the claims.

In the accompanying drawings (4 sheets).—

Figure 1 is a plan view, partly broken away and in section, of an airplane wing or airfoil constructed in accordance with and embodying the 20 present invention;

Figures 2, 3, and 4 are detail sectional views of the airfoil, taken, respectively, along the lines 2—2, 3—3, and 4—4, Figure 1;

Figure 5 is an enlarged detail sectional view of the airfoil, taken approximately along the line 5—5, Figure 2, illustrating particularly a connection between the airfoil and the fuselage;

Figure 6 is a view similar to Figure 1 of a slightly modified airfoil embodying my present 35 invention;

Figures 7 and 8 are detail sectional views, taken approximately along the lines 7—7 and 8—8, Figure 6, respectively;

Figure 9 is a detail sectional view of the modified airfoil of Figure 6, taken approximately along the line 9—9, Figure 7, illustrating a connection between such airfoil and the fuselage;

Figure 10 is an enlarged fragmentary perspective view of the airfoil structure, showing the interlacing and cell-forming connection between ribs of the airfoil, the skin being omitted;

Figure 11 is an enlarged diagrammatic perspective view of a companion pair of the airfoil 50 ribs, illustrating the facile assembling thereof in the formation of the cellular skeleton or framework of the airfoil;

Figures 12 and 13 are enlarged fragmentary sectional views of the airfoil, illustrating in de-

tail the cell-forming interconnection between some of the ribs and the skin of the airfoil;

Figure 14 is a detail sectional view of the airfoil, taken approximately along the line 14—14, Figure 12;

Figure 15 is a fragmentary plan view illustrating a modified type of fuselage and wing or airfoil attachment;

Figure 16 is a detail sectional view, taken approximately along the line 16—16, Figure 15;

Figure 17 is an enlarged fragmentary longitudinal sectional view of the airfoil, illustrating the facile provision in the wing of gasoline or other fuel tanks or containers;

Figure 18 is a detail sectional view, taken approximately along the line 18—18, Figure 17; and

Figures 19 to 25, both inclusive, are fragmentary plan views of modified types of ribs and their interconnection in the cellular formation of an airfoil of my present invention.

Referring now in more detail and by reference characters to the drawings, the wing or airfoil is of so-called geodetic construction and includes a skeleton body or framework A of what may be described as of "honeycomb" or cell structure formed of a plurality of criss-crossed or intersecting and mutually interlocking or interconnected ribs a, each of which is of unique shape particularly adapted and designed for its respective location in the entire wing structure, that is to say, the peripheral or marginal contour of each rib a conforms exactly to the curve or contour of the particular wing-section along which it is disposed.

As best seen by reference to Figures 10 and 11, each rib a is stamped or otherwise formed preferably from relatively thin gauge duralumin or other suitable metallic plate or sheet material and includes a web 1 provided substantially

40 throughout its periphery, except at what may be called its trailing end 1', with a skin-supporting or marginal lateral flange comprising an upper portion 2, a lower portion 2', and a connecting or arcuate nose-portion 2'', the web 1 of each rib a being preferably formed with a plurality of lightening cut-outs 3 each having a marginal or annular lateral rib-stiffening flange 4.

The lower marginal flange 2' of some of the ribs a is at suitably spaced intervals therealong interrupted or cut-away, and such ribs a thereby provided with marginal slots, as at 5, having a longitudinal width substantially equal to the transverse width of the flange and each communicating with a respective kerf 6 extending, as it may be said and with reference particularly to

Figure 11, vertically for a substantial distance upwardly into, and having a width substantially equal to the thickness of, the web 1.

Similarly, certain other or companion ribs *a* are provided along their upper flanged-portions 2 with like or co-operative slots 5' and kerfs 6', the several ribs *a*, when assembled, being inter-fitted and slidably interengaged at the slots 5, 5', and kerfs 6, 6', it being, of course, understood that the slots 5, 5', and kerfs 6, 6', are of such matching dimensions and length that, when a pair of companion ribs *a* are assembled and opposingly interengaged at the kerfs 6, 6', the slot 5 of the one rib *a* will seat and be disposed with surface evenness or smoothness in the slot 5' of the companion rib *a*.

The several ribs *a*, assembled and intersectingly interengaged at the slots 5, 5', and kerfs 6, 6', as described, are fixed together at their respective juncture points by suitable connection-angles 7, which are conventionally riveted in place in the formation thus of a multiple-sectional or geodetic cellular framework A.

The several so rigidly interengaged and connected ribs *a* constituting the framework A are obliquely disposed to the longitudinal axis of the finished airfoil and hence likewise for strain and stress resistance obliquely disposed to the line of flight of the airplane, and at their rear margin 1', the flange-portions 2, 2', of the several ribs *a* are obliquely cut-away for efficient abutment against and connection to a longitudinally extending girder or spar *a'* provided at regularly spaced intervals along its length with laterally presented marginal flanges 8 for permanent connection to the flanges 2, 2', of the ribs *a* primarily for equilibrating any unabsorbed torque or twisting forces. And suitably secured to the rearwardly presented face of the rib or spar *a'*, is a plurality of transversely disposed channel-shaped ribs *a*² spaced longitudinally of the wing and of more or less conventional design and shape to provide the trailing edge of the airfoil, all as best seen in Figures 1 and 13.

The obliquely cellular skeleton or framework A is then covered by and enclosed within a so-called "skin" B, which extends from a point, as at *b*, a short distance inwardly from the leading edge of the airfoil, around the leading edge and rearwardly across the upper face, and finally around and underneath the trailing edge, terminating at a point, as at *b'*, a short distance forwardly from such trailing edge, the remaining underface of the airfoil being covered by a sheet or section 9 of relatively inexpensive fabric material, which may be readily removed and replaced for permitting convenient access to the framework A for repairs and the like, the skin B being by suitable rivets or the like permanently fixed to and flatwise upon the marginal flanges 8 of the enclosed framework A.

The airfoil A is firmly secured to the fuselage C by means preferably of a plurality of conventional opposed angles 10, which are riveted to the abutting ends of the ribs *a* and, in turn, secured to the fuselage framework 11 by conventional mounting angles 12, as best seen in Figures 1, 2, and 5.

Lugs or so-called nuts *n* having lateral flanges 13 are fixed, as by means of rivets 14, to the skin B at spaced points adjacent its outer margin, each lug or nut *n* being centrally provided with a longitudinal bore 15 opening into a diametrically enlarged recess 16 spaced inwardly a short distance from the end of the bore 15 for housing 75

an aligningly apertured fiber or other suitable washer 17, and disposed at the outer longitudinal end of the wing, is a tipmember D, which may be of any conventional pattern or design, and which is provided along its inner margin with an extension-flap 18 overlying the outer marginal portion of the wing skin B and fixed thereto, as by means of suitable screw-members 19' threadedly engaged with the lugs *n* and washers 17, all as best shown in Figure 4.

The modified wing or airfoil shown in Figure 6 comprises a cellular frame A', which includes a plurality of intersecting and interconnected rib-members *a*³ substantially similar in form and structure to the ribs *a*, except that the several ribs *a*³ are so designed and shaped as to extend entirely across the width and throughout the length of the wing in the provision of a completely geodetic structure and thereby eliminate the incorporation therewith of the additional conventional elements designed to provide a trailing edge and wing tip, such as the ribs *a*² and tip D.

As illustrated, the modified frame A' is provided with a skin B' and an underface fabric 9' substantially in the manner described in connection with the frame A and, in the present instance, is fixed to the fuselage C in so-called low wing position by a plurality of pairs of opposed V-shaped angles 19 conventionally riveted to the adjacent ends of the ribs *a*³, the skin B' and underface fabric 9' being also secured against the fuselage C by means of pairs of angle strips 20, 21, all as best seen in Figures 7 and 9.

It has also been found that wings or airfoils constructed in accordance with and embodying my present invention may be very conveniently fixed to the fuselage C by means of a plurality of pairs of opposed triangular plates 22 each joggled along one of its oblique margins, as at 23, for flushwise accommodating the rib flange 2, 2', and provided along its three margins with depending flanges *f* for rivet-connection with the web portions 1 of the ribs *a* or *a*³ and a fuselage member 11, the marginal portion of the wing skin B' and the underface fabric section 9' being securely held in place by means of conventional angle strips 24, all as best seen in Figures 15 and 16.

As shown in Figures 17 and 18, a section of the frame A or A' may be blocked off in the formation of a gasoline tank or container by welding or otherwise hermetically sealing certain selected cut-outs 3 with metallic disks 25 and by hermetically sealing a section of the wing skin B or B' over the top and bottom of the blocked area. The particular lightening cut-outs 3 located within such blocked area may, of course, be left unobstructed to permit free communication between the component parts of the tank, and the skin of the tank having conventional cap-closed filling-openings and the like.

It has further been found that, instead of slotting and kerfing the several ribs *a* or *a*³ for interlocking criss-crossed engagement in frame-formation as described, a plurality of so-called longitudinally zig-zag or corrugated ribs *e* having marginal flanges 26 cut-away to provide engagement corners 27 and socket corners 28 may be employed in the formation of the cellular framework of the airfoil. In the construction of such a wing, a plurality of the ribs *e* may be brought into co-operative engagement, the corner portions 27 of one rib being arranged abuttingly within the socket-corners 28 of the next

adjacent rib and being secured together by a plurality of conventionally riveted angle strips 29, as shown in Figures 19 and 20.

If desired, the "zig-zag" ribs e' may be provided with straight intermediate abutment sections 30 having registering rivet-receiving apertures, which may be secured together in wing formation substantially as shown in Figures 21 and 22. Zig-zag ribs, such as e or e', may be peripherally contoured for longitudinal disposition within the airfoil or may be similarly contoured for transverse disposition, as shown in Figure 23.

If also desired, a plurality of box-shaped or rectangular ribs g provided with a plurality of skin-supporting marginal flanges 31 and formed at their four corners with vertical flattened abutment sections 32 may be employed, as best seen in Figure 24.

Likewise a plurality of short rib sections h may be employed, each section h' having top and bottom lateral skin-supporting flanges 33 and at its opposite outer ends having lateral web extensions providing attachment flanges 34, a plurality of such sections h being assembled and riveted together, substantially as shown in Figure 25. Obviously these latter modifications are most particularly suitable for the fabrication of non-tapered airfoils of the type commonly used in bi-planes and standard training ships, thereby permitting of a relatively small number of different standardized patterns rather than a large number of uniquely shaped supporting ribs.

And with respect to the present airfoils embodying any of such unique ribs in interconnected criss-cross formation, all the ribs cross the median line or longitudinal axis of the wing preferably at a constant angle of 45°, although it should be noted that 45° is not a unique angle, for any other constant angle may be used, and substantially each rib is of a different length, the cells of the wing decreasing toward the tip.

In such wings or airfoils, it may also be stated that the same structure which acts to hold the wing shape or contour serves also to transmit any imposed loads to the body of the airplane without the intervention of a secondary structure of beams, spars, and the like. The fact that the wing uses a rib which is continuous from top to bottom surfaces and from nose to the rear closing channel prevents the squashing or flattening of the wing contour.

Further, the structure is such that production costs are very low, since the wing employs only two basic ribs, as shown. Such ribs, being continuous members, may be cheaply and quickly formed by only two dies, and the inherent simplicity of the mating construction makes feasible the facile assembly of the wing skeleton by untrained labor.

Another great advantage of my wing construction is its ability to withstand abuse without seriously impairing its strength. A load applied at a random point on any one rib is transmitted to a multiplicity of other load resisting elements. For instance, in the wing section shown in either Figure 1 or Figure 6, if one imagines a load applied at a random point on any rib in the central portion of the wing, it becomes evident that this force is further distributed to other ribs, which, in turn, distribute

this force to additional ribs, and so on until the load is evenly resisted by the whole structure. This inter-action characteristic enables the wing to still resist failure even when damaged. This characteristic is of great value in military airplanes, where a wing may be called on to operate satisfactorily even though damaged considerably by bullet holes and tears.

Further, the wing is of exceptional structural rigidity, since all forces imposed upon the leading edge, for instance, regardless of angle of incidence, will nevertheless be distributed in compression throughout the skeleton or framework and ultimately transmitted to the fuselage, and any torque-producing forces or shear stresses which might have a buckling or collapsing effect on the cells would be equilibrated across either one or the other cell-diagonal by placing the skin in tension. In fact, by considering the skin as tension-filaments across the cell-diagonals, it will be evident that the present geodetic wing is a so-called determinant structure, that is to say, a structure for which a complete and precise stress diagram can be prepared.

And the described gas-tank formation may also be made watertight in the provision of an emergency flotation chamber, such as is often required on ships made under government contract. This also is accomplished at not extra weight and little more cost.

And it should be understood that other changes and modifications in the form, construction, arrangement, and combination of the several parts of the airfoil may be made and substituted for those herein shown and described without departing from the nature and principle of my invention.

Having thus described my invention, what I claim and desire to secure by Letters Patent is,

1. An airfoil including a frame comprising, a plurality of straight interlocking ribs having a width substantially equivalent to the thickness of the airfoil, said ribs being obliquely disposed to the leading edge of the airfoil and connected with each other in criss-cross cell formation, each of said ribs further having a peripheral contour conforming to the sectional contour of the airfoil in the plane of such rib.

2. An airfoil including a frame comprising, a plurality of straight ribs having a width substantially equivalent to the thickness of the airfoil, said ribs being obliquely disposed to the leading edge of the airfoil, said ribs further being kerfed at regular intervals for interlocking engagement in criss-cross cell formation, each of said ribs having a peripheral contour conforming to the sectional contour of the airfoil in the plane of such rib.

3. An airfoil including a frame comprising, a plurality of straight interlocking ribs having a width substantially equivalent to the thickness of the airfoil, said ribs being obliquely disposed to the leading edge of the airfoil and connected with each other in criss-cross cell formation, each of said ribs further having a peripheral contour conforming to the sectional contour of the airfoil in the plane of such rib and being provided with a latterly projecting marginal flange for supporting attachment to the skin of the airfoil.

HARRY M. MCKAY.
